FIG. 2.

UNITED STATES PATENT OFFICE.

JOHN HERGESHEIMER, OF PHILADELPHIA, PENNSYLVANIA, ASSIGNOR TO THE CURTIS PUBLISHING COMPANY, OF PHILADELPHIA, PENNSYLVANIA, A CORPORATION OF NEW JERSEY.

MEANS FOR PREVENTING OFFSET IN CONNECTION WITH PRINTING.

No. 897,831.

Specification of Letters Patent.

Patented Sept. 1, 1908.

Application filed May 13, 1908. Serial No. 432,574.

To all whom it may concern:

Be it known that I, JOHN HERGESHEIMER, a citizen of the United States, and a resident of Philadelphia, in the county of Philadelphia and State of Pennsylvania, have invented certain new and useful Means for Preventing Offset in Connection with Printing, of which the following is a specification.

The principal object of the present invention is to prevent offset, that is what might be called blurring, smirching or smearing of the sheets as they are delivered from a printing press in a pile.

In accordance with the present invention the printed sheets are passed through heat radiated from a heater, which may be of the electric variety, and near a single insulated discharger or conductor receiving a high voltage unidirectional current or a high voltage static charge of one polarity, or high voltage impulses of the same sign or polarity; the impulses of opposite sign or polarity, or the other side of the source of unidirectional current or charge of electricity, being sent to earth or grounded with the result that these forces coöperate in setting the ink and preventing offset and incidentally neutralizing static electricity, if present in the paper.

The invention will be claimed at the end hereof, but will first be described in connection with the accompanying drawings which illustrate forms of apparatus embodying features of the invention and chosen for the sake of explanation.

Figure 1, is a more or less diagrammatic side view illustrative of the invention. Fig. 2, is a perspective view illustrating mechanism embodying features of the invention, and Fig. 3, is a diagrammatic view illustrating a modification of the mechanism shown in Fig. 2.

In the drawings 1, are electric heaters, the construction of which is not material, but for the sake of explanation they are shown to consist of bars 2, wrapped with insulating material 3, as of asbestos, upon which are wound coils of wire 4.

5, is a reflector or shield, or both, and it may be lined with asbestos. The shield and bars are shown as supported by means of rods 6.

7, is a conductor or discharger arranged in proximity with the heater and to the side

thereof toward the press. The conductor 7, is properly insulated and is shown as mounted in insulating holders 8. The electric heater is supplied with current from any source in order to heat it.

In the drawings I have shown an alternating current generator 9 having connection by way of conductors 10, through the coils of the heater. The conductor or discharger 7, is connected with a source of high tension unidirectional current or charge or of high tension impulses of the same sign or polarity. A "Wimshurst" static generator having one pole grounded and the other connected with the conductor or discharger 7, is an example of such a source and the sign of the pole or part to which the conductor is connected is immaterial. As being in some ways a more desirable source, I have shown a transformer of which the primary is connected with the generator by conductors 11 and of which the secondary is connected at one end to earth or grounded by a conductor 12, and at the other end to the conductor or discharger 7, through a device or rectifier having an asymmetrical resistance and therefore permitting of the passage of unidirectional current or impulses of like polarity to the conductor or discharger. In Fig. 2, this device or rectifier is shown to comprise a valve tube 13 and in Fig. 3, a spark gap 17, of which a multiple series is illustrated. Inasmuch as the conductor 7 is arranged and connected up in substantially the manner described in British Patent No. 5948 of 1897, it follows that its effect is to remove static electricity from the paper, if the same is present.

In use the described apparatus is arranged in respect to the press and to the printed sheets as they come from the press in the manner shown in Fig. 1; that is to say, it is arranged between the press and the pile of sheets with the discharger or conductor 7 on the press side of the heater 1. The sheets are delivered as shown by the sheet 14 in Fig. 1, above and past the described apparatus. In doing this they move in the direction shown by the arrow. The heater radiates heat upon the sheets as they pass and in passing the sheets are subjected to the results of the silent discharge or leakage which occurs at the conductor 7. Among the effects of this silent discharge or leak mention may be

made of the generation of ozone and the disturbance of the condition of the surrounding air. These effects as well as others, which it is unnecessary to describe in detail in conjunction with heat radiated from the heater cause the ink on the sheets to become so set that offset is obviated.

What I claim is,

1. Means for preventing offset in printed sheets which comprise an electric heater and a single insulated conductor or discharger arranged in proximity with each other and with the moving sheets, and a source of unidirectional high tension current or charge connected with said conductor or discharger and with ground, substantially as described.
2. Means for preventing offset which comprise an electric heater and a discharger operatively arranged in respect to each other, and means for supplying current to the heater and high tension unidirectional current or charge to the discharger, whereby a silent discharge or electrical leakage is effected in

proximity with the heater, substantially as described.

3. Means for preventing offset which comprise a heater and a discharger operatively arranged in respect to each other, and means for supplying high tension unidirectional current or charge to the discharger, whereby a silent discharge or electrical leakage is effected in proximity with the heater, substantially as described.

4. Means for preventing offset in printing which comprise a heater and a single insulated conductor or discharger arranged in proximity with each other and with the moving sheets, and means for charging the discharger with unidirectional charges or impulses, substantially as described.

In testimony whereof I have hereunto signed my name.

JOHN HERGESHEIMER.
